UNITED STATES PATENT OFFICE.

HENRI BERNAY, OF SAN FRANCISCO, CALIFORNIA, ASSIGNOR, BY MESNE ASSIGNMENTS, TO FRED W. THURSTON, OF SAN FRANCISCO, CALIFORNIA.

DRILL.

1,359,318.

Specification of Letters Patent. Patented Nov. 16, 1920.

Application filed February 24, 1919. Serial No. 279,002.

To all whom it may concern:

Be it known that I, HENRI BERNAY, a citizen of the United States, residing in the city and county of San Francisco, State of California, have invented a new and useful Improvement in Drills, of which the following is a specification.

My invention relates to improvements in rock drills and the like wherein a slotted stock operates in conjunction with a pin to maintain a contact between the inner ends of the bits and slots.

The primary object of the present invention is to provide an improved drill having detachable bits;

A further object of the present invention is to provide an improved drill of the character described having improved means for removably securing bits to said drill;

A still further object of the present invention is to seat detachable bits within slots in the stock in such a manner that no shearing strain will be applied to the bit securing means;

It is also an object of the present invention to provide an improved form of a bit for operation in connection with the stock of the drill, said bit having a reduced inner end to provide an enlarged outer end adapted to increase the cutting portion of the bit;

It is still further desired to provide an improved bit of the type described wherein the slots are formed to resist slitting and to prevent a lateral movement of the bit.

I accomplish these several objects by means of the improved device disclosed in the drawings forming a part of the present specification wherein like characters of reference are used to designate similar parts throughout the said specifications and drawings, and in which—

Figure 1 is a front elevation of my improved drill;

Fig. 2 is a vertical sectional view of the drill;

Fig. 3 is a side elevation of Fig. 1;

Fig. 4 is a bottom plan view of Fig. 1;

Fig. 5 is an elevation of one of the bits removed from the stock;

Fig. 6 is a vertical sectional view of the lower portion of a stock taken on line 6—6 of Fig. 1 in the direction indicated; and

Fig. 7 is a detailed view of the retaining pin.

Referring to the drawings the numeral 1 is used to designate a stock having arcuate slots 2 which pass through a central bore 3 of said stock 1.

The bore 3 is provided with an enlarged 60 tapering portion 4 within which is seated the tapered portion 6 of a second stock 7 having a central bore 8 communicating with the central bore 3 of the stock 1.

The inner ends of the slots 2 of the stock 65 1 are provided at their corners and throughout the length thereof with arcuate grooves 9, the purpose of which will hereinafter be more fully set forth.

Arcuate bits 11 are seated within the slots 70 2 and are provided with one cutting edge 12 which follows the curvature of the body, said bits 11 being shaped to fit within the slots 2, the side walls of which are parallel with each other and seat upon those portions 75 of the inner ends of the slots 2 between the grooves 9 therein so that when a pressure is applied to the cutting edges 12 of the bits 11 said pressure will be transmitted to said portions and swage or mushroom said portion into the said grooves 9 thereby preventing the splitting of the stock 1.

The bits 11 are reduced at their inner ends as at 14 to provide a wider cutting edge 12 and also to facilitate in reaming the hole 85 being drilled, said reaming function being carried out by the ends of the bit adjacent the cutting edge 12.

Each bit 11 is provided with a transverse centrally disposed elongated retaining aperture 90 16 the inner ends only of said apertures 16 registering with a transverse channel 18 passing through the stock 1 and the slots 2 and between the inner and outer ends of said slots 2.

A transverse pin 19 is removably mounted within the channel 18 and the retaining or locking apertures 16, said pin 19 thereby engaging the inner ends only of the elongated apertures 16 whereby a pressure applied to the cutting edges 12 of the bits 11 100 will be prevented from shearing the pin longitudinally.

The distance from the inner ends of the apertures 16 to the inner ends of the bits 11 105 is substantially the same as the distance between the inner ends or surfaces of the channel 18 whereby the said inner ends of the bits 11 are firmly seated upon the anvils or portions of the inner ends of the 110

slots 2 between the grooves 9, thereby preventing play or lost motion between the bits and inner ends of the slots.

To prevent a lateral shearing strain upon 5 the retaining pin 19 a rib 21 is provided upon the inner or concaved face of each bit 11 which rib 21 is adapted to engage, when the bits are properly seated within the slots 2, longitudinally disposed grooves 22 within 10 the outer walls of the slots 2.

The pin 19 is split and expanded at one end as at 23 so as to frictionally engage the walls of the channel 18 and thereby prevent inadvertent removal of the retaining pin 19.

15 Having thus described my invention what I claim as new and desire to secure by Letters Patent is—

1. A drill comprising a stock having slots in one end thereof, the side walls of the 20 slots being parallel with each other; bits removably mounted within the slots and provided with transversely disposed apertures; means detachably mounted within the stock for engaging only the inner ends of 25 the apertures to hold the inner ends of said bits against the inner ends of the slots; and means for preventing a transverse movement of the bits relatively to the stock to prevent a shearing strain on the aperture 30 engaging means.

2. A drill comprising a stock having slots therein and grooves extending throughout the length and the bottom of each slot and at the corners thereof; bits removably 35 mounted within the slots and having their inner ends seated upon those portions of the inner ends of the slots between the grooves; and means for retaining the bits in such position.

40 3. A drill comprising a stock having arcuate slots therein and grooves extending throughout the length of the slots and at the corners thereof; arcuate bits removably mounted within the slots and having their 45 inner ends seated upon those portions of the inner ends of the slots between the grooves; and a transverse pin mounted within the stock and bits to retain said bits in such position.

50 4. A bit, arcuate in outline, having a cutting edge following the curvature of the body, said cutting edge being longer than the opposite edge of said body, and provided with a centrally disposed locking 55 aperture.

5. A bit, arcuate in outline, having a cut-

ting edge following the curvature of the body, said cutting edge being longer than the opposite edge of the bit, and provided with an elongated, centrally disposed locking 60 aperture.

6. A bit, having a cutting edge on one side thereof longer than the length of the opposite edge, and provided with a transverse centrally disposed locking aperture, 65 and a rib on one face thereof to prevent lateral movement of said bit when mounted within a suitable stock.

7. A bit, arcuate in outline, having a cutting edge following the curvature of the 70 body, said cutting edge being longer than the opposite edge, and having a transverse centrally disposed locking aperture and a rib on one face thereof to prevent lateral movement of the bit when mounted within 75 a suitable stock.

8. A bit, arcuate in outline, having a cutting edge longer than the edge opposite, and provided with a rib formed on the concaved face thereof to prevent lateral movement of the bit when in a suitable stock and likewise provided with a transverse centrally disposed locking aperture.

9. A drill comprising a stock having slots in one end thereof; bits removably mounted 80 within the slots and provided with transverse centrally disposed locking apertures; and a split pin removably mounted within the stock and engaging only the inner surfaces of the bit apertures to retain said bits 90 within the slots.

10. A drill comprising a stock having slots in one end thereof and longitudinal grooves formed in the outer walls of each slot; bits removably mounted within the 95 slots and provided with longitudinal ribs adapted to engage the grooves in the walls of the slots so as to prevent lateral movement of said bits within the slots.

11. A drill comprising a stock having 100 slots in one end thereof and longitudinal grooves formed in the outer walls of each slot; bits removably mounted within the slots and provided with longitudinal ribs adapted to engage the grooves in the walls 105 of the slots so as to prevent lateral movement of said bits within the slots; and means for preventing a longitudinal movement of the bits within the slots.

In witness whereof I hereunto set my 110 signature.

HENRI BERNAY.
